BOILER CLEANER

Lucian Clark Brown, La Feria, Tex.

Application December 4, 1934, Serial No. 755,973

2 Claims. (Cl. 122—389)

The object of this invention is to provide simple means for mechanically removing from the water in a steam boiler those impurities which, if not removed, form scale upon the flues and walls 5 of the boiler, and by interfering with the transmission of heat to the water, retard the production of steam and cause a waste of fuel. The invention is illustrated in the accompanying drawings and consists in certain novel features which will be 10 hereinafter first fully described and then more particularly defined in the appended claims.

In the drawings:

Figure 1 is a plan view of the improved device in position in a boiler.

15 Figure 2 is a side view of the same.

Figure 3 is a transverse section.

Figure 4 is a plan view of a portion of the device on a larger scale.

Figure 5 is a longitudinal section of the same.

20 Figures 6, 7 and 8 are transverse sections on the lines 6—6, 7—7 and 8—8, respectively, of Figure 5.

Figure 9 is an edge view of a cover or top member.

25 The boiler 1 with the flues 2 may be of any known or preferred dimensions and arrangement and are shown in a conventional manner only.

According to the present invention, boxes 30 of oblong form are placed upon the uppermost flues and are arranged in two or more parallel series, as shown in Figure 1. The boxes nearest the front end of the boiler having their front ends connected by a cross pipe 4 which is coupled to a pipe 5 leading through the front end of the boiler and connected by a valve 6 with a blow-off nozzle 7. The front ends of all the boxes are tapered to form spouts 8, the spouts on the front boxes being coupled to the pipe 4 and the spouts 35 of the intermediate and rearmost boxes being each engaged in an opening in the rear wall of the box immediately in front of it, and lock nuts 9 are mounted on the spouts to prevent their premature or accidental withdrawal. The rear 40 end wall 10 of the rearmost boxes are imperforate, as shown in Figures 5 and 8. Removably secured upon each box by screws 11, is a cover or top 12 having transverse slots 13 therein and having a depending flange or plate 14 at the rear of each 45 slot, the front face of the flange being flush with the rear wall of the slot, as clearly shown in Figure 5. Bosses 15 are formed on the cover at its rear end and pipes 16 are threaded into said bosses and rise therefrom.

50 The boxes are set in place with their tops at

the water level in the boiler and the pipes 16 extending into the steam space of the boiler. As the water heats, it will circulate and the impurities rise to its surface in a scum which will float over the boxes and drop through the slots in their tops, the flow being from the front of the boiler toward the rear thereof. The matter deposited in the boxes is permitted to accumulate until the valve 6 is opened whereupon the steam will enter through the pipes 16 and blow the accumulations 5 out through the discharge nozzle 7. It will be noted that the several flanges 14 depend close to the bottoms of the boxes and their lower edges are turned forward so that the entering scum will be directed toward the front ends of the boxes and 10 the steam which is admitted to blow out the accumulation will be caused to flow over the bottoms of the boxes and operate with a high degree of efficiency. It will be noted, upon reference to Figure 1, that the slots in the front boxes are 15 relatively narrow and that the slots in each box to the rear are wider than the slots in the box in front of it, this arrangement minimizing the noise at the front of the boiler and providing 20 larger exits at the rear where the water agitation is less pronounced. It is also to be noted that each box discharges through a tapered nozzle so that the discharged matter will enter the next forward box with considerable velocity which 25 will carry it well forward of the steam entering 30 that box. As the covers are removable, a cover having slots of any desired width may be placed on any box so that any demand may be met according to the size of the boiler, the nature of the 35 water, and any other controlling conditions.

Having described my invention, what I claim is:

1. A boiler-cleaning apparatus comprising a plurality of boxes arranged end to end and adapted to be supported upon the uppermost flues of the boiler, a slotted scum collecting top on each box, 40 a steam pipe entering the top at the rear end of each box, a valve controlled outlet for the front-most box, the rearmost box having an imperforate rear end and each of the other boxes having an 45 opening in its rear end, and a tapered nozzle on the front end of each box having the smallest end secured in the opening in the box in front of it so that the discharged matter will enter the next forward box with considerable velocity which will 50 carry it well forward of the steam entering that box.

2. A boiler-cleaning apparatus comprising a series of boxes arranged end to end, the rearmost box having an imperforate rear end and each of the other boxes having an opening in its rear end, 55

a tapered nozzle on the front end of each box having the smallest end secured in the opening in the box in front of it, a scum collecting top on each box, and a steam pipe entering each top near the rear end of the box, said tops having transverse slots with the slots in the top of each box

wider than the slots in the top of the box next in front so that noise will be minimized at the front of the boiler and larger entrance slots for material will be provided at the rear of the boiler where the water agitation is less pronounced.

LUCIAN CLARK BROWN.
